UNITED STATES PATENT OFFICE.

JOHN W. KRUEGER, OF DARWIN, MINNESOTA.

COMBINED MOP HOLDER AND WRINGER.

1,049,242.

Specification of Letters Patent. Patented Dec. 31, 1912.

Application filed March 19, 1912. Serial No. 684,661.

To all whom it may concern:

Be it known that I, JOHN W. KRUEGER, a citizen of the United States, and a resident of Darwin, in the county of Meeker and State of Minnesota, have invented a new and Improved Combined Mop Holder and Wringer, of which the following is a full, clear, and exact description.

The objects of my invention are to provide an improved form of mop holder and wringer; to provide a mop having a construction adapting it peculiarly for combination with a scrubbing device; to improve the elements entering into the operation and supporting means of the mop head device; and to provide a scrubbing device having novel means for holding a scrubbing brush and peculiarly adapted for co-operation with my novel mop heads and their appurtenances.

The invention will be described herein-after in detail in connection with the illustrated example given as one structural embodiment of my invention.

Reference is to be had to the accompanying drawings forming a part of this specification, in which similar characters of reference indicate corresponding parts in all the figures.

Figure 1 is a side elevation of the combined mop holder and wringer, showing a partial embodiment of my invention; Fig. 2 is a plan view; Fig. 3 is a detail longitudinal section of the brush-holding device and the forward mop head; Fig. 4 is a transverse sectional elevation of the forward mop head; and Fig. 5 is a transverse vertical section of the rear mop head and a portion of the handle thereof.

The general description of the main elements is as follows: The main handle carries at its forward end a fixed mop head, and below the main handle is an auxiliary handle carrying a second mop head, the two heads being adapted to hold the ends of a mop rag of any suitable form. The auxiliary handle is normally held at its rear end by a latch and at an intermediate point it has a support in which the handle may reciprocate, to move the second head toward and from the fixed head in washing the mop rag. The intermediate support of the auxiliary handle is mounted to rock, and it also forms bearings in which the auxiliary handle can turn, for revolving the second head relatively to the first one, and thereby twisting

the mop rag, to wring it. The securing means of the fixed head which fits the main handle is especially designed to receive the supporting arm of a brush-holding device comprising depending clamps adapted to detachably hold the scrubbing brush at a point in front of the fixed mop head.

In constructing the device in the form illustrated, a main handle 10 is provided of suitable length, and carries at its forward end a suitable fitting 11, carrying a fixed mop head 12. The fitting 11 may be in the form of a socket, as shown, into which the handle 10 extends and fits tightly, and the head proper 12 is joined to the socket 11 by a downwardly and forwardly inclined fork 13, the forked form of the member 13 constituting a skeleton frame for lightness. The mop head 12 ranges transversely and has a depression or recess 14 in its top surface which receives the depending gripping rib 15 of a clamp 16, said clamp extending at its ends above the top of the head 12, and receiving screw studs 17 having wing nuts 18, for clamping the mop rag 19 in the depression or recess 14 beneath the gripping rib 15.

Below the main handle 10 is supported an auxiliary handle 20, having at its forward end the second mop head 21, which may be formed with a groove 22 and a clamp 23 secured by studs 24 and wing nuts 25 or their equivalents, in a manner similar to the corresponding clamp devices of the fixed head 12. The auxiliary handle 20 is supported intermediate its ends on a bracket 26, having a sleeve 27 or equivalent device for securing the bracket to the main handle 10. The bracket 26 depends from the under side of the socket 27, and comprises side arms that have bearings 28 that receive trunnions 29 on a supporting block 30, said block having forward and rear bearings 31. The rear end of the auxiliary handle 20 is provided with a locking head 32, which receives a latch pin 33 on a latch 34, said latch having also, parallel with the latch pin 33, a forwardly extending integral guide rod 35, which is provided with a compression spring 36, the arrangement being such that the latch 34 may be pressed rearwardly against the pressure of the spring 36, to withdraw the pin 33 from the locking head 32 of the auxiliary handle 20. When the auxiliary handle is released from the latch it may be reciprocated in the bearings 31, to move

the rearward mop head 21 toward and from the fixed head 12, for manipulating the mop rag 19 in washing the same. The block 30 on which the bearings 31 are formed is 5 mounted to rock on its trunnions 29 to accommodate the movements of the rod 35, and make its manipulation convenient, so that it need not be reciprocated in a direct line. Similarly the rod 20 is adapted to be 10 rotated in the bearings 31 so that the mop head 21 may be turned relatively to the fixed head 12, for twisting the rag 19, to wring the same. The rod 34 has sliding movement in depending arm 38 of a hanger 37 fitted 15 on the handle 10, said arms being spaced apart as shown, to receive the locking head 32 of the auxiliary handle 20. It will be observed that the head 32 constitutes a hand hold or grip for convenience in manipulating 20 the auxiliary handle 20.

The brush-holder 40 is provided with a supporting arm 41 which seats on the top surface of the socket 11 of the forward mop head 12, which socket is formed with an 25 oblong block or lug 43 that fits a longitudinal slot 44 in the arm 41 of the brush-holder, the block 43 having a screw stud 42. The upper face of the arm 41 has a series of transverse notches 45, any one of which may 30 receive a gripping block 48 of inverted V-shape, said block 48 being clamped against the arm 41 by a wind nut 47 on the screw stud 42. The arrangement is such that the arm 41 may be moved inward or outward 35 to engage the gripping block 48 with any one of the notches 45, to support the brush 39 a greater or less distance in front of the forward mop head 12. The brush 39 is clamped in place in the brush-holder be- 40 tween a fixed jaw 49 and a movable jaw 50,

said movable jaw being adapted to be opened or closed by the movement of a knurled nut 51 on a threaded rod 52, which has bearings at its ends in the upwardly projecting blocks 53 on the top surface of 45 the brush-holder 40. The nut 51 is fitted on the rod 52 between lugs 54 on the movable jaw 50 so that by turning the nut to the right or left the jaw 50 is opened or closed.

Having thus described my invention, I 50 claim as new, and desire to secure by Letters Patent,—

1. In a mop, mop-holding means comprising a main handle having a mop head, an auxiliary handle having a mop head, a block 55 mounted on the main handle to rock thereon and having bearings in which the auxiliary handle may reciprocate and rock, a bracket in the rear of said bearing, and a latch on said bracket for holding the aux- 60 iliary handle against movement.

2. In a mop, the combination of a handle having a mop head, a depending bracket on said handle, a block mounted to rock on said bracket and having bearings, an auxiliary 65 handle mounted in said tilting block to reciprocate therein and to turn, the auxiliary handle having a mop head at its forward end and a lateral latch head at its rear end, a bracket depending from the main handle 70 in the rear of the first mentioned bracket, and a latch on said bracket for engaging the lateral head on the auxiliary handle.

In testimony whereof I have signed my name to this specification in the presence 75 of two subscribing witnesses.

JOHN W. KRUEGER.
